(No Model.)

E. THUEMMELER.
Air Engine.

No. 233,125.

Patented Oct. 12, 1880.

FIG. I.

FIG. II.

WITNESSES

David Weller,
D.P. Cowl

INVENTOR

Edward Thuemmler

UNITED STATES PATENT OFFICE.

EDWARD THUEMMLER, OF LITTLE ROCK, ARKANSAS.

AIR-ENGINE.

SPECIFICATION forming part of Letters Patent No. 233,125, dated October 12, 1880.

Application filed March 5, 1880. (No model.)

To all whom it may concern:

Be it known that I, EDWARD THUEMMLER, a citizen of the United States, residing at Little Rock, in the county of Pulaski and State of Arkansas, have invented a new and useful Air-Engine, of which the following is a specification.

My invention relates to air-engines; and the object is to improve the construction of those air-engines in which a bell or air-shifter is reciprocated and the confined air alternately heated and cooled on opposite sides or ends of said bell or shifter; and the invention consists in the construction and arrangement of the parts, as will be hereinafter more fully described, reference being had to the accompanying drawings and the letters of reference marked thereon.

In the accompanying drawings, Figure 1 is a vertical longitudinal section of an air-engine according to my construction. Fig. 2 is a modification of the same for a vertical engine.

In the drawings, A represents a cylinder of a reciprocating engine, in which a piston, a, moves. This piston is made in the form of a double piston, or of two pistons, each properly packed, set such distance apart as will admit of the stroke without either of the pistons passing the openings x x', placed in the cylinder about the middle thereof, and connected together in such manner that, while forming a single piston, an annular space shall exist between said pistons of sufficient volume to permit therein a free circulation of lubricating and cooling material admitted to and flowing from the cylinder through said openings x x'.

To the forward end of the piston there is connected a piston-rod, a', which passes through a suitable stuffing-box, and is connected to an ordinary connecting-rod, b, that connects to the crank c, which imparts motion to the machinery. At the opposite end of the piston is firmly attached, in any suitable manner, a bell or air-shifter, B, preferably made in the form of a hollow cone made double, and the space between its walls or shells filled with suitable non-conducting material. Said material may be extended into the interior of the piston.

A casing, C, is connected directly to the end of the cylinder A, on the same side as the bell and of a similar shape, and extending back

and around the bell and into the hollow part thereof so as to entirely inclose it. A sufficient space is left between the casing C and the bell B, so as to allow the latter to move freely backward and forward in the line of motion and to the extent of the stroke of the piston.

The casing C forms the reservoir or principal air-container of the engine. It is also made double, and part of its length—about one-half, more or less—permits of a free circulation of water to keep that end cool, while the other part is intended for the circulation of the hot air from the furnace and the products of combustion, this end being thereby kept hot. This part is connected to a furnace, D, provided with grate-bars and all the necessary appliances of a furnace, and in the space between the shells thereof may be arranged spiral or other shaped flanges or guides, d, by which a circuitous passage is formed, so as to somewhat retard the products of combustion until they reach the chimney E. The bell B is supported and guided at the end opposite the piston by one or more bars, f, firmly attached at that end, moving in suitable channels made in the extended shell of the reservoir or through stuffing-boxes.

Near the cylinder A is arranged a tank, F, for holding lubricating material, and this tank, made air-tight, is connected, by pipes g h and the openings in the cylinder x x', with the annular space within the cylinder and between the double pistons in such manner that a circulation is kept up in and between said tank and cylinder. This lubricator-tank is preferably inclosed with a water-jacket, and may be connected by suitable pipes m n, for the purpose of circulation, with the water-jacket of the principal reservoir. Attached to and communicating with the interior of the cylinder A at the end nearest the crank, by the pipe i, is an air-chamber, O, filled with air of any required density and pressure. This chamber is connected with the interior of the air-reservoir C by the pipe k, fitted with the valve p, which is operated by a governor. The engine is fitted with supply and drain cocks, a safety-valve, and suitable air-pumps for supplying and compressing air into the engine until the working pressure and density are obtained.

and to restore any loss by waste or leakage when running. Suitable expansion-joints *y y'* are inserted between the cylinder and the reservoir, and between the hot and cold parts of the latter, to take up unequal expansions of the various parts heated to different temperatures.

In the modification, Fig. 2, is represented a vertical engine whose construction is similar to that of Fig. 1. In this case the bell is attached to the piston-rod *a*, which is provided with a yoke, *l*, in which the crank-pin moves. The piston-rod is then extended beyond the yoke and attached to the piston, which moves in a cylinder, *G*, open at its lower end to the atmosphere, while its upper end is connected by pipes *r r'* with the reservoir.

The operation of my engine, referring to Fig. 1, is as follows: The cocks and valves being closed and the engine filled with air at the ordinary atmospheric pressure, the piston is brought to the greatest distance from the crank and the fire lighted. The air, being in front of the bell and disposed upon the hot surfaces of the reservoir, is heated, expands, and propels the piston forward, at the same time forcing the air in the cylinder into the chamber *O* and producing a compression in said chamber. Having reached the limit of the forward stroke, the bell will have shifted the air from the forward or hot to the back or cold end of the reservoir, where it is greatly cooled during the time required by the crank to pass its forward dead-point, and loses a great part of its expansive power, so that the expansive force residing in the air-chamber *O* as the result of the compression produced during the forward stroke comes into effectual operation in producing the return-stroke, compressing the air in the reservoir *C* and shifting same to the forward end of said reservoir, where it is re-heated and ready to pass through the same cycle of changes and effects as that just traced. Part of the power developed in the manner described is applied to operate the supply air-pump, which, by the operation of the engine, is arranged to condense the air in the engine, gradually injecting successive quantities from the atmosphere until the pressure is attained in the chamber *O* and reservoir *C* at which the engine is required to be run. During such condensation the valve *p* is momentarily opened at frequent intervals, and the proper equilibrium of pressures in the chamber and the reservoir thus secured. When the desired pressure has been attained the air-pump is set to inject only an equivalent for the air lost in waste and leakage, or a smaller pump put in operation for the latter purpose. The governor will regulate the speed of the engine whenever the normal speed is exceeded by allowing the valve *p* to open, and thus establishing as near an equilibrium between the chamber *O* and reservoir *C* as the case requires, the valve

closing when the speed is reduced, and remaining closed until the speed rises too high. Opening the valve *p* beyond the limit allowed the governor stops the engine, which starts again when the said valve is closed.

Rigidly connecting my bell and piston greatly simplifies the machinery, and the form of the conical bell and casing or reservoir keeps the air always disposed on the hot or cold surfaces, as the case may be, in a thin annular sheet, most advantageous for the rapid exchange of heat therein.

By causing my lubricating material to circulate in the cylinder, and then cooling said material in the tank *F*, I may safely employ a high degree of heat in my reservoir without injury to the working parts and rubbing-surfaces of the engine, cooled as described.

By means of the air-chamber *O*, employed as described, my engine can be worked under high and proportionally advantageous pressure.

For the sake of brevity, I have in the above specifications employed the word "air" to represent the material whose expansive properties, under the effects of heating and cooling, are employed to produce power and motion, as described. Said material may, however, consist of any vapor, gaseous, or liquid substance exhibiting similar properties under similar conditions.

Having thus described my invention, what I claim, and desire to secure by Letters Patent, is—

1. In an air-engine, the bell or air shifter *B*, made in the form of a hollow cone, reciprocating in the reservoir *C*, of conforming shape, all substantially as shown and described.
2. In an air-engine, the bell or air-shifter *B*, rigidly connected to the piston *a*, and moving in unity therewith, substantially as shown and specified.
3. In an air-engine, the air-chamber *O*, connected with and open to the cylinder at the crank end of same, as and for the purpose set forth.
4. In an air-engine, the combination of the reservoir *C* and the air-chamber *O* with the pipe *k* and valve *p*, as and for the purpose set forth.
5. In an air-engine, the combination of the double piston *a* with the cylinder-openings *x x'*, the pipes *g h*, and the lubricator-tank *F*, as and for the purpose set forth.
6. In an air-engine, the method of cooling the working parts by means of lubricating material passed into the cylinder, and from thence through a cooling tank or vessel, *F*, substantially as shown and specified.

EDWARD THUEMMLER.
